HOLDER ATTACHMENT FOR SHARPENING
SAFETY RAZOR BLADES

Peter C. Rhegas, Detroit, Mich.

Application May 23, 1944, Serial No. 536,929

4 Claims. (Cl. 51—221)

This invention relates to an improved holder attachment for a razor blade of the wafer-type having a frame reinforcement extending along one edge to hold the blade for sharpening. It is adapted to hold the blade for use in a sharpening device of the general character described in my co-pending application, Serial Number 529,318 filed April 3, 1944.

Such co-pending application disclosed a holder adapted to support a wafer-type blade provided with a linearly extending slot. Such a blade is typified by the commercial blades of the Gillette type. Many wafer-type safety razor blades are not provided with a linearly extending slot and the holder attachment disclosed in this application is adapted to accommodate these blades. Many wafer-type razor blades are provided with a frame reinforcement extending parallel to the cutting edge and along the opposite margin of the blade. The improved holder attachment of this application is designed to accommodate these blades.

The blade holder disclosed in my co-pending application above referred to exhibited a base provided with an upright positioning lug adapted to be received through a linear slot in the blade to properly position the blade for sharpening. Such holder was adapted particularly to accommodate blades of the Gillette type referred to above. Unless a blade was provided with such a slot, it was not receivable within the holder described in such co-pending application. The purpose of the holder attachment of this application is to receive and properly support a blade regardless of whether the blade is provided with such a linearly extending slot or not and the attachment itself is adapted to be secured to the holder disclosed in the co-pending application to properly position the blade thereupon.

The improved holder herein described is simple, inexpensive and adapted to readily receive a blade for use therein or to permit withdrawal of the blade therefrom. The blade is securely held by the attachment for sharpening and the attachment is adapted to be securely positioned upon a holder of the character described in my said co-pending application.

Other objects, advantages and meritorious characteristics of the invention will appear more fully from the following specification, appended claims and accompanying drawing wherein:

Fig. 1 is a plan of a holder of the character shown in my co-pending application, Ser. No. 529,318, having the improved holder attachment of this application positioned thereon.

Fig. 2 is a vertical sectional view taken on the line 2—2 of Fig. 1.

Fig. 3 is a plan of one embodiment of the holder attachment which forms the subject of this application.

Fig. 4 is a plan of a modified embodiment of the holder attachment of Fig. 3.

Fig. 5 is a plan of a second modified embodiment of the holder attachment of Fig. 3.

Fig. 6 is a perspective of a double edged wafer-type safety razor blade and a detachable spring clip reinforcement frame adapted to be received over one edge of the blade.

The holder which forms the subject matter 15 of the earlier filed application to which reference has been made hereinabove, is illustrated in Figs. 1 and 2 and comprises a base 10 formed of two thicknesses of sheet metal and provided with upright side walls 14 which serve as a 20 handle whereby the holder may be reciprocated. A blade positioning lug 16 projects upwardly from the base as shown in Figs. 1 and 2. In the earlier filed application referred to hereinabove such lug was adapted to be received through the 25 linear slot of a safety razor blade to properly position the blade.

This holder was preferably provided with a bale-like element 18 pivoted at 20 to the side walls 14 of the holder. This bale element had 30 a front extension 22 which was adapted to engage the forwardly projecting portion of the blade throughout its length whereby such forwardly projecting portion of the blade might be depressed evenly throughout its length against 35 a flat honing surface upon which the holder was supported for reciprocation. This construction and the operation thereof was described in the co-pending application hereinabove referred to.

40 In the instant application, there is disclosed a holder attachment in the form of a spring clip general identified as 24, which clip is adapted to receive and securely hold in the proper position a wafer-type blade of the character 45 shown in the drawing. This holder attachment comprises a pair of complementary jaws 26 and 28 held under inherent spring tension toward each other to grip a safety razor blade, such as 30, received therebetween. The razor blade 50 illustrated is provided along one linear margin with a reinforcement frame 32.

The two jaws of the holder are cut away at 34 providing complementary apertures. When a razor blade of the character indicated as 30 in 55 Fig. 2 is properly received between these two jaws

the frame reinforcement 32 is received within the aperture 34 substantially within the thickness of the two jaws 26 and 28 as shown particularly in Fig. 2. The aperture 34 is illustrated in Figs. 1, 2 and 3 as having a width sufficient to accommodate along one margin of the reinforcement frame 32 received therein the blade positioning lug 16 of the holder as shown in Figs. 1 and 2.

In the construction shown in Figs. 1 and 2, the blade itself is gripped between the two jaws of the holder attachment and such attachment is then positioned upon the holder itself and the projection of the lug 16 through the aperture 34 properly positions the attachment so that the blade is projected forwardly of the front margin of the holder the proper distance for accurate sharpening. The blade together with the holder attachment may be tilted to depress the beveled cutting edge of the blade against a flat honing surface upon which the blade holder rests. On the other hand, if the blade is sufficiently flexible it may be flexed without tilting so as to bring its beveled cutting edge properly against the honing surface.

In Fig. 4 the aperture 34 is shown as notched at 35 along one margin so as to receive within the notch the projecting lug 16 of the holder. The notch 35 is of the proper length to receive the lug whereby the holder attachment is held against displacement relatively upon the holder.

In Fig. 5 the holder attachment 24 is shown as provided not only with the aperture 34 but with a slot 36, which slot extends parallel to the aperture. Such slot is of a size to receive the projecting lug 16 of the holder and support the attachment against displacement upon the holder. Figs. 4 and 5 therefore represent embodiments which would not permit lateral shifting of the attachment with respect to the holder as might result from the use of the attachment shown in Figs. 1, 2 and 3.

A large variety of blades are provided with permanent frame reinforcements 32 of the character shown in Fig. 1 but there are also blades shaped as shown in Fig. 6. In this figure there is illustrated a blade which is double-edged and which is not provided with any linearly extending slot. In order to support this kind of a blade with the holder attachment here illustrated, such blade, which is here indicated as 38, is shown as provided with a separable spring clip frame reinforcement element 40 adapted to be snugly gripped over one cutting margin of the blade by its inherent spring tension. Such a blade so equipped may then be positioned upon the holder as herein illustrated in the manner heretofore described. This attachment therefore complements my improved holder of said earlier filed application and enables any blade, whether provided with a linear slot or not, to be supported upon the holder in a proper manner for sharpening as described in the aforementioned co-pending application.

What I claim is:

1. A holder attachment for sharpening a safety razor wafer-type blade having a frame reinforcement extending along one linear margin of the blade, said holder provided with a pair of complementary jaws spring urged toward each other and having opposed linearly extending blade engaging portions adapted to grip opposite sides of the blade received therebetween along the frame reinforcement of the blade, said jaws provided with an aperture adapted to receive the frame reinforcement of the blade gripped between the jaws, and a flat plate like supporting device having an upper surface portion adapted to support said holder attachment and provided with a positioning part adapted to engage said holder to position the same thereon.

5 10 15 20 25 30 35 40 45 50 55 60

2. A holder attachment for sharpening a safety razor wafer-type blade having a frame reinforcement extending parallel to the cutting edge of the blade and along the opposite margin of the blade, said holder provided with a pair of complementary jaws spring urged toward each other to grip opposite sides of the blade therebetween throughout its length and along said reinforcement frame, said jaws provided with an aperture to receive the reinforcement frame of the blade substantially within the thickness of the jaws, one margin of said aperture being notched to receive a positioning lug extending parallel to the reinforcement frame of the blade gripped between the jaws.

3. A holder attachment for sharpening a safety razor wafer-type blade having a frame reinforcement extending parallel to the cutting edge of the blade and along the opposite margin of the blade, said holder provided with a pair of complementary jaws spring urged toward each other to grip opposite sides of the blade therebetween throughout its length and along said reinforcement frame, said jaws provided with an aperture to receive the reinforcement frame of the blade gripped between the jaws, said jaws provided with a slot extending parallel to the aperture and adapted to receive a positioning lug.

35 40 45 50 55 60

4. A holder attachment for sharpening a safety razor wafer-type blade having a frame reinforcement extending parallel to the cutting edge of the blade and along the opposite margin of the blade, said holder provided with a pair of complementary jaws spring urged toward each other to grip opposite sides of the blade therebetween throughout its length and along said reinforcement frame, said jaws provided with an aperture to receive the reinforcement frame of the blade gripped between the jaws, said jaws provided with a slot extending parallel to the aperture and adapted to receive a positioning lug.

50 55 60

5. A holder attachment for sharpening a safety razor wafer-type blade having a frame reinforcement extending parallel to the cutting edge of the blade and along the opposite margin of the blade, said holder provided with a pair of complementary jaws spring urged toward each other to grip opposite sides of the blade therebetween throughout its length and along said reinforcement frame, said jaws provided with an aperture to receive the reinforcement frame of the blade gripped between the jaws, said aperture being oversize the reinforcement frame to receive a positioning lug extending along the margin of said frame.

PETER C. RHEGAS.
